UNITED STATES PATENT OFFICE.

WILLIAM C. HOMAN, OF MERIDEN, CONNECTICUT, ASSIGNOR TO LEWIS T. WILCOX,
OF PEEKSKILL, NEW YORK.

WICK HOLDER.

Application filed May 28, 1925. Serial No. 33,335.

To all whom it may concern:

Be it known that I, WILLIAM C. HOMAN, a citizen of the United States, residing at Meriden, in the county of New Haven and State of Connecticut, have invented an Improvement in Wick Holders, of which the following is a specification.

As heretofore constructed liquid fuel burners have been fitted with wick holders adapted to be engaged by suitable means for moving the wick holder to adjust the wick carried thereby to position for use. So far as I am aware these wick holders have usually been made with a plurality of apertures adapted to be engaged in one portion of the wick holder by a suitable pinion or suitable device which is revoluble, and connected to a shaft and hand wheel or otherwise to move the wick holder and adjust the wick to position. In this type of wick holder however, due to the engagement of the pinion or similar device with only one portion thereof there is a tendency for the wick holder to wedge or to move unevenly in the casing in which the wick holder is contained, and this results in an uneven portion of the wick projecting beyond the peripheral portion of the casing, and causing an uneven flame from the wick when the burner is in use.

The object of my present invention is to overcome these disadvantages, and to provide a wick holder adapted to be simultaneously engaged in oppositely disposed portions thereof by devices whereby in adjusting the wick to position a uniform movement is imparted to all parts of the wick holder, resulting as will be understood, in a corresponding movement of the wick, so that a uniform flame is produced at all portions of the wick, and the tendency of the wick holder to wedge, because of the application of the actuating devices to one portion only thereof, is entirely obviated.

To this end in carrying out the invention the wick holder made in accordance therewith is preferably adapted to be received in an annular space between the walls of a liquid fuel burner, and at an end thereof, preferably the inner end, is provided with oppositely disposed longitudinal slots so constructed as to have the corresponding edges defining these slots formed with teeth, which constitutes racks adapted to be simul-

taneously engaged by a suitable pinion mechanism to cause a uniform movement in all parts of the wick holder in shifting the same and the wick carried thereby to position for use in the liquid fuel burner, as will be hereinafter more particularly described.

In the drawing Fig. 1 is a plan of one of the blanks from which my improved wick holder is preferably made.

Fig. 2 is a similar view of the other blank.

Fig. 3 is a section on line 3—3, Fig. 4, the same being on a somewhat enlarged scale.

Fig. 4 is an elevation of the improved wick holder and a wick carried thereby.

Fig. 5 is a section on line 5—5, Fig. 4, on a somewhat enlarged scale.

Fig. 6 is a section on line 6—6, Fig. 4.

Fig. 7 is a section on line 7—7, Fig. 4, and on a somewhat enlarged scale, and

Fig. 8 is a central sectional elevation illustrating a form of liquid fuel burner in which my improved wick holder is adapted for use.

The wick holder made in accordance with this invention is preferably formed from blanks comprising plates of suitable sheet metal or other material. One of these plates is indicated at 10 and the other at 11. Along its upper or outer edge the plate 10 may be provided with a series of apertures 12, and similarly the plate 11, with a series of apertures 13.

As indicated the plate 10 is slotted at 14, 15 and 16, and adjacent the opposite end is provided with tongues 17, 18 and 19; similarly adjacent one end the plate 11 is slotted as indicated at 20, 21 and 22, and at the other end is provided with tongues 23, 24 and 25. The plate 10 is provided with a cut 26, extending inwardly from one end thereof, and a corresponding cut 27 from the other end thereof. In a similar manner and in like positions the plate 11 is provided with cuts 28 and 29. The cuts 26 and 27 in the plate 10 provide for sections 30 and 31, adapted to be turned in therefrom to engage a portion of the wick, which as will be understood has been slotted for this purpose. In a similar manner the cuts 28 and 29 in the plate 11, provide for sections 32 and 33, adapted to be turned in to also engage portions of the wick. The section 32 of the plate 11 is provided with a series of slots 34, and in like manner and in corre-

sponding positions the section 33 of the plate 11 is provided with a series of apertures or slots 35.

In assembling these plates to form the tubular wick holder the tongue at 17 is passed through the slot 20, the tongue 18 through the slot 21, and the tongue 19 through the slot 22 to connect adjacent ends of these plates. In a similar manner the tongue 23 is passed through the slot 14, the tongue 24 through the slot 15 and the tongue 25 through the slot 16. The tube is then pressed in a suitable form to turn the tongues down to position, it being understood by this structure that the burners may be made of uniform diameter and the parts thereof connected in proper alignment without adjustment by any other means. The sections 30 and 31 of the plate 10 are then turned in to assume positions substantially as indicated in Fig. 3 so as to engage a wick, and in like manner the sections 32 and 33 are turned in for a like purpose, and also to provide a plurality of teeth 36 and 37, forming racks on corresponding edges defining slotted portions of the wick holder thus formed by turning in the sections 30, 31, 32 and 33. These sections are turned in so as to engage a wick indicated at 38, which at its inner end may also be engaged by upturned projections 39 and 40 provided for this purpose at the inner edge of the wick holder thus formed.

A liquid fuel burner constructed for the use of the improved wick holder as hereinbefore described is illustrated in Fig. 8, and preferably consists in a casing comprising an outer wall 41, and an inner wall 42, suitably interlocked at their inner or lower ends as indicated at 43, to provide an annular space between the walls for the reception of the wick holder and the wick carried thereby. This liquid fuel burner as illustrated in this figure of the drawing may be suitably supported from a supply pipe 44 carrying the liquid fuel thereto, and a bracket 45 extending between the supply pipe and a transverse support 46, extending across the lower or inner end of the burner or otherwise.

The wick holder is actuated by a gear rod 47, extending across the inner wall and through the same so that the end portions thereof act as pinions in engaging with the teeth 36 and 37 forming the racks in the corresponding edges defining the slotted portions of the wick holder. This toothed rod 47 is preferably operated in a sleeve bearing 48, extending across and suitably connected to the diametrically opposite portions of the inner wall 42. The toothed rod 47 may be turned in either direction by a shaft 49. This shaft 49 may be made an integral part of the toothed rod or connected thereto, and extending therefrom in any suitable manner.

This shaft 49 passes through and is journaled in a plug 50, adapted to be turned down in a socket 51, suitably connected to the outer wall of the burner, and also containing a collar 52, between which and the inner end of the plug 50 a packing may be employed to form a tight joint between the shaft and the outer wall of the casing of the burner. At its outer extremity this shaft 49 may be fitted with a hand wheel 54, the outer surface of which is preferably knurled, and by which, it will be understood this shaft 49 may be turned in either direction to actuate the toothed rod, and thereby simultaneously engage the racks formed in the wick holder to impart a uniform movement to oppositely disposed portions of the wick holder, and corresponding movement to the wick thereby preventing any tendency of the wick holder to wedge in the casing, and effecting a uniform projection of the outer end of the wick from all portions of the periphery of the casing to obtain a uniform flame from the wick when the burner is in use.

I claim as my invention:

1. A wick holder comprising a body member having oppositely disposed longitudinal slots therein, and means associated with the corresponding edges defining said slots for simultaneous engagement with an actuating device for imparting a uniform movement to all parts of the said body member.

2. A wick holder comprising a cylindrical body member having oppositely disposed longitudinal slots, and means associated with corresponding edges defining said slots for simultaneous engagement with an actuating device for imparting a uniform movement to all parts of the body member.

3. A wick holder comprising a cylindrical body member having longitudinal slots in oppositely disposed positions therein, the corresponding edges defining said slots being adapted to be engaged by an actuating device for simultaneously moving the body member in either direction from opposite sides thereof.

4. A wick holder comprising a cylindrical body having oppositely disposed longitudinal slots therein, a series of teeth formed in corresponding edges defining said slots forming racks adapted to be simultaneously engaged by an actuating device to impart a movement in either direction to the said wick holder from oppositely disposed portions thereof.

5. A wick holder comprising a cylindrical body member made of connected plates, the said plates having inturned sections providing oppositely disposed slots in the said wick holder, and devices associated with the corresponding edges defining said slots for simultaneous engagement with actuating devices for imparting a movement to the

said wick holder from oppositely disposed portions thereof.

6. A cylindrical wick holder comprising connected plates of sheet material adapted to receive and carry a wick, the said plates having oppositely disposed inturned sections forming oppositely disposed slots therein, and a series of teeth forming racks in cor-

responding edges defining the said slots, which racks are adapted to be engaged by an actuating device for imparting a uniform movement simultaneously to oppositely disposed portions of the said wick holder.

Signed by me this 16th day of May, 1925.

WILLIAM C. HOMAN.
